BATHING SUIT

David Watinsky, Mount Vernon, N. Y.

Application August 19, 1937, Serial No. 159,857

6 Claims.

(Cl. 2—67)

This invention relates to improvements in bathing suits and has for a principal object the provision of a bathing suit of the "dressmaker type" comprised of a bodice and skirt preferably in one-piece, an undershirt forming a lining for said bodice, and a pair of "panties" detachably secured to said undershirt.

Another object of the invention is the provision, in a bathing suit of the "dressmaker type" having an undershirt forming a lining for the bodice of the dress, of a reinforcing member secured to said undershirt portion to form therewith a brassière, said member extending downwardly and being faced with one row of "zipper" fasteners, and the provision of a pair of "panties" provided with a like row of "zipper" fasteners adapted to be placed in cooperative relation with or removed from cooperative relation with said first row of fasteners thereby eliminating the necessity of providing other openings in the suit for the purpose of ingress or egress. The suit and the panties are "zipped" apart and put on separately after which they may again be "zipped" together.

A further object of the invention is the provision, in bathing suits of the character described, of panties made up, in part, of rubber (such as "lastex"), and due to the perishable nature of such materials as compared to the materials in the remainder of the suit, such panties may readily be replaced several times before the suit proper is discarded.

Still another object of the invention is the provision of a brassière and of "panties" adapted to be placed in quickly detachable cooperative relation with each other on a wearer's body, the junction member being permanently secured to said brassière and detachably secured to said "panties".

Other objects will be obvious to those skilled in the art.

Referring now to the drawing—

Figure 1 is a front view of the new and improved bathing suit;

Figure 2 is a back view of the suit shown in Figure 1;

Figure 3 is a front view of the suit shown in Figure 1 with a portion of the front broken away to show the "panties" detached; and

Figure 4 is a vertical medial section of the bathing suit shown in Figure 1.

In describing the new and improved bathing suit, the main or outer garment will be termed a "dress"; the inner garment forming a lining for the bodice of the dress will be termed an "under-

shirt"; and the detachable drawers portion of the suit will be termed "pants".

Referring to the drawing, the dress generally designated by the numeral 10 consists of a bodice portion 11 and a skirt portion 12. Between the arm-holes 13 and 14, respectively, and the neck-opening 15, the narrowest portions 16 and 17 form in effect shoulder straps. The neck-opening in the back may be cut low, if desired, at 18 so that a portion of the wearer's back may be exposed. 10 Suitable belt strings 19 and 20 are secured to the dress on opposite sides thereof and may be tied in a bow at the rear, as indicated in dotted lines at 21. Within the bodice 11 an undershirt 22 is provided. This undershirt is provided with 15 arm and neck openings matching the arm-holes 13 and 14 of the suit and the neck-openings 15 and 18. The undershirt 22 is preferably stitched to the bodice along the outlines of the arm and neck openings and preferably along the 20 waist-line 23 across the back of the bodice.

The front portion of the shirt has secured thereto by stitching, indicated at 24, a reinforcing member 25. The reinforcing member 25 may be of any desired shape, but in the preferred embodiment of the invention it is pentagonal form. In the preferred embodiment one apex of the pentagon joins the front neck opening 15 at the point indicated by the numeral 26. This reinforcing member strengthens the undershirt in front and forms in effect a brassière. 30

The lower edge of the reinforcing member 25, as may be seen in Figure 3, has secured thereto a row 27 of fasteners of the "zipper" type, the function of which will presently be described.

The back of the suit may be provided with a placket 28 extending from the opening 18 downwardly to a point below the waist, and suitable buttons 29 or other fastening devices may be provided for opening and closing the placket 28.

The "panties" 30 may be made of any suitable material; however, in the preferred embodiment of the invention the "panties" are made of materials which include rubber or the like, a typical example of which is known on the market as 45 "Lastex".

It has also been found preferable in using such materials for "panties" to have the grain or the stretch of the material extend laterally so that "panties" of a given length may fit a plurality of 50 sizes of wearers. The waist 31 of the "panties" may be finished off with a suitable hem or binder which may also be stretchable.

The waist 31 may also have secured thereto in front, a row 32 of fasteners similar to the 55

row 27 and adapted to be placed in cooperative relation with the fasteners in the row 27. The actuator member 33 of the fastener preferably remains on the row 32.

5 In placing the fastener members in cooperative relation with each other, a pilot member 34 at one end of the row 27 is inserted into an opening in the member 33 provided for the purpose, thereby facilitating the operation of securing the "pan-
10 ties" to the suit.

10 In some models the placket 28 may be omitted and in place thereof suitable trimmings may be provided, in which case the suit may be put on and taken off over the wearer's head, the "pan-
15 ties" having previously been detached.

15 In Figure 4, the brassiere portion of the suit is shown in cooperative relation with the "panties" 30, the "panties" being detachably secured to the reinforcing member 25, and the member 25 being 20 permanently secured, by stitching, to the brassiere portion of the suit. This arrangement is not only applicable to bathing suits, but may be used for ordinary wear and particularly for dance sets in which case the shoulder straps 16 and 17 25 would be substantially narrowed and the sides of the brassiere would also be substantially narrowed and arranged to encircle the body.

30 Although a preferred embodiment of the invention is herein shown and described, it is obvious that many other embodiments of the invention may be made without departing from the spirit of the invention as set forth in the annexed claims.

What is claimed is:

35 1. In a bathing suit, in combination, a dress 40 comprised of a skirt and a bodice having arm and neck openings formed therein, an undershirt having arm and neck openings coincident with said first arm and neck openings, said undershirt being permanently secured to said bodice along the outlines of said openings, means secured to said undershirt for supporting a row of separable fasteners, a pair of panties, a row of separable fasteners secured to said panties and adapted to be placed in cooperative relation with said first row of fasteners, and an actuator carried by said first row and adapted to engage or disengage the fasteners in said rows.

50 2. In a bathing suit, in combination, a dress 55 comprised of a skirt and a bodice having arm and neck openings formed therein, an undershirt having arm and neck openings coincident with said first openings, means permanently securing said bodice and said undershirt together along the outlines of said openings and along the waist-line from one side across the back to the other side, a reinforcing member secured to the front portion of said undershirt and forming therewith a brassiere, a row of separable fasteners secured 60 to said reinforcing member, a pair of panties, a row of separable fasteners secured to said panties and adapted to be placed in cooperative relation with said first row of fasteners, and an actuator carried by said first row and adapted to engage or disengage the fasteners in said rows.

65 3. In a bathing suit, in combination, a dress 70 comprised of a skirt and a bodice having arm and neck openings formed therein, an undershirt having arm and neck openings coincident with said first openings, means permanently se-

curing said bodice and said undershirt together along the outlines of said openings and along the waist-line from one side across the back to the other side, thereby allowing said dress to hang free in front, a polygonal reinforcing member 5 secured to the front portion of said undershirt and forming therewith a brassiere, a row of separable fasteners secured to said reinforcing member, a pair of panties formed in part of elastic material, a row of separable fasteners secured to the upper portion of said panties in front and adapted to be placed in cooperative relation with said first row of fasteners, and an actuator carried by said first row and adapted to engage or disengage the fasteners in said rows. 15

4. In a bathing suit, in combination, a one-piece dress comprised of a skirt and a bodice having arm and neck openings formed therein, an undershirt having arm and neck openings coincident with said first openings, means permanently securing said bodice and said undershirt together along the outlines of said openings and along the waist-line from one side across the back to the other side leaving the dress hanging free in front, a reinforcing member secured to the front portion of said undershirt and forming therewith a brassiere, a row of separable fasteners secured to the bottom line of said reinforcing member, a pair of panties including elastic web material, a row of separable fasteners secured to the top line of said panties in front and adapted to be placed in cooperative relation with said first row of fasteners, and an actuator carried by said first row and adapted to engage or disengage the fasteners in said rows, said actuator 35 being accessible when said skirt is raised in front.

5. In a bathing suit, in combination, a one-piece dress comprised of a skirt and a bodice having arm and neck openings formed therein, a knitted undershirt having arm and neck openings coincident with said first openings, means permanently securing said bodice and said undershirt together along the outlines of said openings and along the waist-line from one side across the back to the other side, a reinforcing member 40 secured to the front portion of said undershirt and forming therewith pockets for the breasts, a row of separable fasteners secured to the lower edge of said reinforcing member, a pair of panties formed of a combination including elastic materials, a row of separable fasteners secured to the top front line of said panties and adapted 45 to be placed in cooperative relation with said first row of fasteners, and an actuator carried by said first row and adapted to engage or disengage the 55 fasteners in said rows.

6. A bathing suit comprising an over-dress having a short skirt and a bodice, an undershirt forming a lining for and permanently secured to said bodice, a reinforcing member secured to 60 the mid-portion of the front of said undershirt and forming therewith a brassiere, a pair of panties formed at least in part of elastic material, and a separable fastener including a row of members secured to said reinforcing member, 65 and a cooperating row of fastening members secured to said panties, and an actuator cooperating with both said rows of members for detachably securing said panties to said reinforcing member.

DAVID WATINSKY.
